DESIGN FOR A HAMMER HEAD

John E. Lydle, Akron, Ohio

Application June 12, 1945, Serial No. 120,032

Term of patent 14 years

(Cl. D93—4)

To all whom it may concern:

Be it known that I, John E. Lydle, a citizen of the United States and a resident of Akron, in the county of Summit and State of Ohio, have invented a new, original, and ornamental Design for a Hammer Head, of which the following is a specification, reference being had to the accompanying drawing, forming part thereof.

In the drawing:

Figure 1 is a top plan view of a hammer head embodying the new design;

Figure 2 is a side elevation thereof;

Figure 3 is an end elevation as viewed from the left of Figure 2; and

Figure 4 is an end elevation as viewed from the right of Figure 2.

What is claimed is:

The ornamental design for a hammer head, as shown.

JOHN E. LYDLE.
